UNITED STATES PATENT OFFICE.

MICHAEL KRAJNAH AND JOHN MADUNICKY, OF DANBURY, CONNECTICUT.

MACHINE FOR HARDENING HATS.

1,343,729.

Specification of Letters Patent. Patented June 15, 1920.

Application filed December 23, 1919. Serial No. 346,877.

To all whom it may concern:

Be it known that we, MICHAEL KRAJNAH and JOHN MADUNICKY, citizens of the Czecho-Slovakia, residing at (1) 7 Maple 5 avenue, Danbury, (2) 459 North Main St., Danbury, county of Fairfield, State of Connecticut, have invented an Improvement in Machines for Hardening Hats, of which the following is a specification.

10 The object of the present invention is to harden the felt of hat bodies. The unshaped bodies are dipped in water and are then piled in stacks, preferably twelve bodies to a stack, in flatwise fashion. A stack is then 15 rolled up in burlap or other suitable material, and placed in our novel machine and rolled therein to harden the felt.

With this object in view, the invention comprises the novel construction, arrangement and combination of parts as herein-after fully described and clearly shown in the accompanying drawing.

In the drawing,

25 Figure 1 is a side elevation of the device; and

Fig. 2 is a vertical longitudinal section thereof.

The frame 10 consists of uprights 11, 12 and 13 at opposite sides thereof, horizontal braces 14 and 15 for the uprights, and upper and lower cross connecting members 16, 17 and 18. Carried on the frame is an obliquely arranged bar 19 having a hook 20 at its uppermost end. Also on the frame are the 30 obliquely arranged braces 21. Pivoted to braces 22 on these braces is a table 23 of sufficient size to accomplish its purpose, and having attached to it the bearing blocks 24 for a shaft 25 which extends across the machine and the ends of which are mounted 35 in the brackets 22. When in horizontal position a portion of the lower surface of the front half of the table rests on upper cross connecting member 18. Secured to 40 opposite braces 15 and between the uprights 11 and 12, are bearing blocks 26 which have journaled therein a crank shaft 27 carrying a belt pulley 28. Two oblique bars 29 are each pivotally mounted at their lower ends 45 on the crank shaft adjacent the outer sides of the bearing blocks 26. At suitable points the oblique bars 29 are provided with rectangular openings 30 in which are blocks 31 arranged to reciprocate therein. The slides 50 are held in the slots in any convenient manner, as by a tongue and groove connection.

The crank shaft 27 carries a crank arm 32 to which is pivoted by means of bearing blocks 33 a plate 34 which corresponds in width with the table. Near its upper end 60 and adjacent its side edges, the plate 34 carries bearing blocks 35 for a shaft 37 journaled in sliding blocks 31.

The oblique bars 29 have screw eyes 38 adjacent their upper ends, and to the screw 65 eyes are attached ropes 39 which travel over guide pulleys 40 on the frame and have attached thereto weights 41 to counterbalance the oblique bars. The upper ends of the oblique bars are connected by a cross piece 70 42, which has attached thereto intermediate its ends a chain 43 any of the links of which may be engaged with hook 20 to regulate the pressure upon the bundle of hat bodies.

The opposite uprights 13 at the front of 75 the frame have pivotally attached to their outer sides as shown at 45 the toggles 46 each having an upper arm 47 and a lower arm 48 pivoted together at 49. The upper arms are each pivotally attached at their upper ends 80 to the brackets 50 which are secured, as shown, to oblique bars 29. Arranged at the front of the machine and carried by the front ends of the arms 48 of the toggles is a treadle 51.

Table 23 has attached to it near its rear end and adjacent its side edges, ropes 52 which pass over guide pulleys 53 on the upper arms of the toggles and the other ends of which are attached to the treadle. The 90 table is counterbalanced by means of weights 54 suspended from the rear edge thereof.

The apron is indicated as a whole by 55. It comprises ropes 56 and round rods 57, shown as threaded thereon, which lie in parallel relation to each other, the element as a whole being thoroughly flexible. This apron is of sufficient width and length to effectually roll the bundles of hat bodies therein. The ends of the ropes are attached, respectively, to table 23 and plate 34, near the front edges thereof, and in working position the apron partly infolds the bundle of hat bodies and rolls it as the plate 34 reciprocates and oscillates as herein-after described. 100 As shown, the lower portion of the apron rests on the table, and the upper portion thereof is stretched taut by its connection with plate 34. A guard 58 at the front of the machine prevents the accidental dropping of the bundles of hat bodies as they are placed in or removed from the apron.

In operation, the foot applied to the treadle opens the toggles and gives a downward pull on ropes 52, thereby forcing plate 34 upward and table 23 downward toward 34 upward and table 23 downward toward 5 a horizontal position. This opens out the apron so that a bundle of hat bodies may be placed therein. Upon relieving the pressure on the treadle the toggles will return to their normal positions, the plate 34 will 10 drop to the lowermost position allowed by the chain 43, weights 54 will tilt the table to an oblique position and take up the slack in ropes 52, and the bundle of hat bodies in ropes 52, and the bundle of hat bodies will roll forward into the fold of the apron. 15 The table and plate are now in their working position. Adjustments of the chain 43, as heretofore mentioned, to regulate the pressure on the bundle of hat bodies, are made by passing any desired link over the 20 hook 20.

Power is now applied to pulley 28 to revolve the crank shaft and its crank. As will readily be understood, a combined reciprocatory and oscillatory motion is thereby 25 imparted to plate 34, and the sliding blocks are caused to reciprocate in the openings in the oblique bars. The weight of the oblique bars and plate, as adjusted by means of chain 43, will keep the oblique bars in their 30 working position, and the combined reciprocatory and oscillatory movement of the plate will impart the desired rolling movement to the apron. After the machine has been started its operation may be continuous. 35 When a bundle of hat bodies has been sufficiently treated, the operator by pressure on the treadle, opens the toggles which places the plate, apron and table in the position shown in Fig. 2. As soon as the hardened 40 bundle of hat bodies has been removed and a new one placed on the apron, the operator removes his foot from the treadle and the operation proceeds as before.

What we desire to claim is:

45 1. A machine of the character described, comprising a pivoted table and a reciprocating and oscillating plate, each carrying one end of an apron, and means for bringing the table and plate into operative relation.

50 2. A machine of the character described, comprising a pivoted table and a plate, each carrying one end of an apron, means for bringing the table and plate into operative relation, and means for imparting a combined reciprocating and oscillating movement to the plate.

55 3. A machine of the character described, comprising a pivotally mounted table, a plate carried by movable oblique bars, the table and plate each carrying one end of an apron, means for bringing the table and plate into operative relation, and means for imparting a reciprocatory and oscillatory motion to the plate.

60 4. A machine of the character described,

comprising a pivotally mounted table, a plate carried by movable oblique bars, an apron attached to said table and plate, respectively, and means for imparting a combined reciprocatory and oscillatory motion 70 to the plate.

5. A machine of the character described, comprising a table and a plate, said table being pivotally attached to a frame, and said plate being carried by a movable oblique 75 bar, an apron carried by said table and plate, toggle levers for bringing the table and plate into operative relation, and a crank shaft for imparting a combined reciprocatory and oscillatory motion to the 80 plate.

6. A machine of the character described, comprising a table and a plate, each attached to the ends of an apron, means for bringing the table and plate into operative relation, 85 and means for imparting operative movement to the plate.

7. A machine of the character described, comprising a table and a plate, the table pivotally carried by an oblique brace and 90 the plate carried by a movable oblique bar pivotally attached to a frame and being reciprocable from a crank shaft, the front ends of the table and plate, respectively, carrying an apron, means for bringing the table 95 and plate into operative relation and for moving them apart for insertion and removal of the work, and means for actuating the crank shaft.

8. A machine of the character described, 100 comprising a table pivotally attached to a frame, a plate pivotally attached to slides working in movable oblique bars, an apron attached to the table and plate, means for bringing the plate into operative relation 105 with the table, and other means for reciprocating and oscillating the plate.

9. In a machine of the character described, a table, a plate, and an apron, means for moving the table and plate from and toward 110 each other, and means for reciprocating and oscillating the plate.

10. In a machine of the character described, a table, a plate, and an apron, means for moving the table and plate from and 115 toward each other, and means for reciprocating the plate.

11. In a machine of the character described, a table and a plate, said table pivotally secured on a frame and said plate pivotally attached to slides in movable oblique 120 bars, an apron having its ends attached to the table and plate, respectively, means for bringing the table and plate into operative relation and means for reciprocating the 12 slides.

12. In a machine of the character described, a table and a plate, said table pivotally secured and carrying one end of an 13 apron, said plate carrying the opposite end

of said apron and being pivotally attached to slides in movable oblique bars pivotally carried by a crank shaft, the crank arm of said crank shaft rotatively engaging the lower end of said plate, means for moving the table and plate into operative relation, and means for actuating the crank shaft, whereby the rotary motion of said crank arm imparts a combined reciprocatory and oscillatory movement to the plate.

13. In a machine of the character described, a table and a plate, said table pivotally secured and carrying at its front end one end of an apron, said plate carrying at its 15 front end the opposite end of the apron and being pivotally attached to slides in movable oblique bars pivotally carried by a crank shaft mounted on the frame, the oblique bars being adjustably carried by a chain engageable 20 with a hook on an overhead support carried by the frame, the crank arm of said shaft

rotatively engaging the lower end of said plate, means for moving the table and plate into operative relation, and means for actuating the crank shaft, whereby the rotary 25 motion of said crank arm imparts a combined reciprocatory and oscillatory movement to the plate, thus operating the apron.

14. An apron for a hat machine of the character described, comprising ropes carrying round rods transversely arranged with 30 relation thereto.

15. A machine of the character described, comprising a pivoted table, a reciprocating plate, and an apron, said apron being operatively located between said table and said 35 plate.

In testimony whereof we affix our signatures.

MICHAEL KRAJNAH.
JOHN MADUNICKY.
